[57] CLAIM

The ornamental design for a telescoping automatic transmission modulator pin gauge, as shown and described.

DESCRIPTION

FIG. 1 is a front elevational view of a telescoping automatic transmission modulator pin gauge showing my new design, the rear being a mirror image thereto;

FIG. 2 is a right side elevational view thereof, the left side being a mirror image thereto;

FIG. 3 is a front elevational view thereof in an extended position;

FIG. 4 is a top plan view thereof, the bottom plan being a mirror image thereto;

FIG. 5 is a longitudinal cross sectional view of FIG. 1.
